UNITED STATES PATENT OFFICE.

HARVEY R. CURRIER, OF DANVILLE, ILLINOIS.

DIRIGIBLE-HEADLIGHT CONTROL.

1,157,764.

Specification of Letters Patent.

Patented Oct. 26, 1915.

Application filed June 30, 1915. Serial No. 37,278.

To all whom it may concern:

Be it known that I, HARVEY R. CURRIER, a citizen of the United States, residing at Danville, in the county of Vermilion and State of Illinois, have invented certain new and useful Improvements in Dirigible-Headlight Controls, of which the following is a specification, reference being had to the accompanying drawings.

My present invention relates to new and useful improvements in apparatus for steering the headlights of motor vehicles and as one of its principal objects aims to provide an improved apparatus of this character which is relatively simple in construction and may, consequently, be cheaply manufactured and readily applied to any standard type of automobile, without requiring any changes or alterations in the construction thereof.

Another object is to interpose in the connection between the spindles of the lamps and the transverse rod, which is connected to the front wheel knuckles, a connecting element which is of such nature that while it will cause the turning of the lamp spindles and consequently the lamps in accordance with the transverse movement of the rod, it will compensate for the vertical movement of the lamp when the automobile is passing over rough ground and the springs are, therefore, yielding and expanding.

The above, and other incidental objects of a similar nature, which will be herein-after more specifically treated, are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced to practice, and throughout the several views of which similar reference numerals designate corresponding parts, Figure 1 is a top plan view; Fig. 2 is a detail view in front elevation of the mechanism at one side of the vehicle; Fig. 3 is a detail view in side elevation of the mechanism at the other side of the vehicle; and Fig. 4 is a detail section of the lower end of one of the spindles, showing the engagement of the operating arm therewith.

In the embodiment of my invention illus-

trated in the accompanying drawings, the lamps generally designated by the numerals 10 and 11, are mounted in the usual manner in supporting yokes or brackets 12 and 13, which members are preferably formed upon the upper ends of spindles or shafts 14 and 15. The spindles 14 and 15 are mounted for rotation in the vertically disposed bearing sleeves 16 and 17, which members are formed as an integral part of, and depend from bracket blocks 18 and 19. The members 18 and 19 are secured upon the upper faces of the chassis members 20 and 21, by means of bolts or equivalent fastening devices, indicated at 22. As will be seen upon reference to Fig. 2, the lower terminals of the spindles depend a considerable distance below the forward springs of the automobile.

As a means for bracing the bearing sleeves, I provide a transverse rod 23, which member is terminally secured by bolts or equivalent fastening devices to the laterally extending apertured ears 24 formed on the bearing sleeves. These rods serve also to prevent the loosening of the bearing sleeves through vibration. It is desired to explain that the terminals of the rod may be connected to the bearing sleeves by clamps or any other fastening means.

As a means for turning the spindles in accordance with the deflection of the front wheels of the vehicle, I provide a transverse steering rod 25, a pair of relatively fixed arms 26 and 27, and a pair of loosely mounted arms 28 and 29. The terminals of the transverse steering rod 25 are pivotally connected in the manner shown in Fig. 1 to the knuckles of the front wheels, so that the deflection of the front wheels will cause a corresponding transverse movement of the steering rod. In this connection, it is to be explained that the steering rod 25 shown in the drawings, represents the transverse rod which is ordinarily provided for connecting the knuckles of the front wheels of a motor vehicle. In case the steering gear of the particular vehicle to which the invention is to be applied is of such nature that the transverse rod is not present, or is so located that it will be impractical to attach the arms 26 and 27 to it, an additional transverse rod may be connected to the knuckles of the front wheels.

The rear ends of the members 26 and 27 are extended vertically and are formed as two piece clamps, as shown best in Fig. 3.

Bolts, indicated at 30 are, of course, employed in securing the two elements of the clamp about the transverse steering rod.

The forward ends of the members 26 and 5 27 are provided with ball sockets, indicated at 31. These sockets 31 receive the ball heads 32 which are formed in the ends of the members 28 and 29, as in Fig. 1. In order to permit the lamps and spindles to 10 move vertically, relative to the members 26 and 27, under the action of the vehicle springs, I form the lower terminals 34 of the lamp spindles with perforations or eyes 33, these eyes being chamfered from the 15 middle or outwardly flaring, so as to permit the free vertical motion of the arms 28 and 29, without binding in the spindle eyes. As will be seen from Fig. 4, the arms 28 and 29 thus have angular movement in a vertical 20 plane with respect to their respective spindles and are also movable longitudinally through the eyes of the spindles, but engage with the spindles for unitary movement when the arms 29 are shifted in a horizontal 25 plane.

From the foregoing description and upon reference particularly to Fig. 1 of the accompanying drawings, it will now be apparent that the transverse movement of the 30 steering rod, as a result of the deflecting of the front wheels of the vehicle, will be communicated to the spindles of the lamps by means of the arms 26 and 27 and 28 and 29. The turning of the spindles will, of course, 35 result in the turning of the lamps, since the yokes 12 and 13 are relatively fixed upon the upper ends of the spindles.

I now desire to direct particular attention 40 to the fact that the ball and socket connections between the members 26 and 28, and 27 and 29, together with the peculiarly

formed eyes in the spindles, are adapted to take up the vertical movement of the arms 28 and 29 when the springs of the vehicle 45 are yielding or expanding. Also these ball and socket joints constitute pivotal connections.

In reduction to practice, it has been found that the form of this invention illustrated 50 in the drawings, and referred to in the above description as the preferred embodiment, is the most efficient and practical; yet realizing that the conditions concurrent with the adoption of this device will necessarily vary, 55 it is desirable to emphasize the fact that various minor changes in the details of construction, proportion and arrangement of parts may be resorted to, when required, without sacrificing any of the advantages 60 of this invention, as defined by the appended claim.

What is claimed, is:—

In a headlight steering mechanism for vehicles, a lamp supporting spindle rotatably supported by the vehicle and having its lower extremity provided with an eye, an arm disposed through the eye of the spindle, a transverse rod, an arm relatively fixed upon the rod and having an extremity 65 provided with a socket, the first named arm having an extremity provided with a ball mounted in the socket of the second named arm to afford a joint freely connecting the adjacent extremities of said first named and second named arms.

In testimony whereof I hereunto affix my signature in the presence of two witnesses.

HARVEY R. CURRIER.
